UNITED STATES PATENT OFFICE

ABRAM L. ZENT, OF DAYTON, OHIO

COIN-CONTROLLED APPARATUS

Application filed January 7, 1929. Serial No. 330,732.

This invention relates to a coin controlled apparatus and more particularly to a coin controlled vending machine.

One object of the invention is to provide such an apparatus having a coin chute adapted to receive coins of different values and having means for selectively controlling the operations of the article ejectors, or other parts to be operated, according to the value 10 of the coin deposited in that chute.

A further object of the invention is to provide such an apparatus having means for preventing the operation of the parts to be operated when there is no coin in the chute or when 15 certain types of coin substitutes are deposited in the chute.

A further object of the invention is to provide such an apparatus in which the several selecting and controlling operations will be effected by the manipulation of a single operating device.

A further object of the invention is to provide such an apparatus having a delivery device of such a character that the articles to be delivered will be prevented from bouncing 20 out of the delivery receptacle when they are discharged into the same.

Other objects of the invention will appear as the apparatus is described in detail.

In the accompanying drawings Fig. 1 is a front elevation of an apparatus embodying my invention with the casing in section and partly broken away; Fig. 2 is a side elevation, partly broken away, and with the casing in section; Fig. 3 is a detail view of the coin controlled actuating device showing the positions assumed when there is a five cent coin in the chute; Fig. 4 is a similar view showing the positions assumed when there is a ten cent coin in the chute; Fig. 5 is a section taken on the line 5—5 of Fig. 1; Fig. 6 is a section taken on the line 6—6 of Fig. 2; Fig. 7 is a section taken on the line 7—7 of Fig. 2; and Fig. 8 is a section taken on the line 8—8 of Fig. 2; Fig. 9 is a fragmentary detail of the article 40 ejector.

In these drawings I have illustrated one embodiment of my invention and have shown the same in connection with a machine designed primarily for vending metal checks 45

such as are used in the operation of coin controlled telephones. It will be understood, however, that this particular embodiment has been chosen for the purposes of illustration only and that the apparatus may take various forms and may be used for various purposes without departing from the spirit of the invention.

In that form of the invention here illustrated the apparatus comprises a main frame 50 mounted on a base 11 and having at its upper end a transverse top member 12 which constitutes a supporting plate for the receptacles or magazines which contain the articles to be vended. In the present machine 55 there are three magazines, 13, 14 and 15. The supporting plate 12 has a discharge opening 16 adjacent to each magazine and the several discharge openings communicate with a common delivery chute 17. The mechanism 60 for ejecting the articles or checks from the magazines comprises an ejector arranged to enter the lower portion of one of the magazines and discharge the lowermost coin therefrom. As has been stated, the present machine 65 is designed primarily for vending telephone checks each of which has a value of 70 five cents. The machine is constructed to deliver to the customer either one check upon the payment of five cents or two checks upon 75 the payment of ten cents and in order to accomplish this the three magazines are provided and one of these magazines, 13, has an individual ejector, which will eject one coin from that magazine upon each operation 80 thereof. The other magazines, 14 and 15, are provided with a double ejector adapted to simultaneously eject the lowermost coin from each of said magazines. Obviously if the articles to be vended were of different values 85 each of the magazines might be provided with an individual ejector. The single ejector for the magazine 13 is shown at 18 and the double ejector for the magazines 14 and 15 is shown at 19. Each ejector is in the form of a plate 90 slidably mounted in a guideway between the supporting plate 12 and the bottom of the magazine. Secured to each ejector is a lug 20 which depends therefrom through a slot 21 in the supporting plate 12 and serves both to 95 100

impart movement to the ejector and to guide the same. As here shown, each lug 20 comprises parallel ears between which is arranged a stud 22, preferably in the form of a roller, which is engaged by the slotted end of a rock arm 23. The rock arm 23 for the double ejector 19 is rigidly secured to a shaft 24 which is journaled in the side members of the main frame, and the rock arm for the single ejector 18 is rigidly secured to a tubular shaft or sleeve 25 rotatably mounted upon the shaft 24. Each of the shafts has a rearwardly extending crank arm 26 which is acted upon by a spring 27 to retain the ejector normally in its retracted position. The telescoping shafts 24 and 25 project beyond one side member of the main frame and have rigidly secured thereto, respectively, arms 28 and 29 each of which is provided at its lower end with a contact portion here shown as laterally extending lugs 30 and 31, respectively. The arm 29, which is connected with the tubular shaft of the single ejector 18, is of a length somewhat greater than the length of the arm 28 of the shaft 24 of the double ejector and the lug 31 of the arm 29 is of such a length that it will lie directly beneath the lug 30 of the arm 28. Both lugs are preferably provided in their forward edges with V-shaped recesses.

30 The machine is provided with a single coin chute 32 which opens through the front wall of the casing and the lower end of which is closed or obstructed by a laterally extending lip or detent 33 which is carried by a movable structure 34 which, in the present instance, is pivotally mounted on the main frame 1 on an inclined axis, as shown at 35. The structure, which is preferably in the form of a flat arm or narrow plate, has a finger 36 projecting beyond the axis thereof which is engaged by a spring 37 which tends to move the main portion of the structure and the detent 33 toward the coin chute and to retain the detent normally in a position to prevent the escape of a coin from the chute. This coin chute is adapted to receive coins of different denominations and, in the present machine, it will receive either a five cent coin or a ten cent coin. Means are provided for selecting 40 and operating one or the other of the ejector arms 28 and 29 according to the value of the coin in the chute. As here shown, this means comprises an actuating member 38, which may be in the form of an elongated plunger, 45 preferably tapered toward one end and having its small end adapted to enter the recess in the contact portion of either of the ejector arms. The actuating member 38 is pivotally mounted on the upper end of an upright support or lever 39 the lower end of which is pivoted on the main frame at 40. The actuating arm is therefore capable of pivotal movement to move the end thereof into line with the contact portion of the selected ejector arm 50 and is longitudinally movable, by the swing-

5 ing movement of the support 39, to engage and actuate the selected ejector arm. Swinging movement may be imparted to the support 39 in any suitable manner. In the present instance, the support is provided with a longitudinal slot 41 to receive a stud 42 carried by an operating device or key bar 43, slidably mounted on the main frame of the machine and inclined downwardly and rearwardly with relation to the support 39. The key bar may be mounted in any suitable manner, as by providing the same with longitudinal slots 44 to receive studs 45 fixed in the main frame. At its outer end it is provided with a finger piece or key 46 for depressing the same. A spring 47, connected at its lower end with the key bar and at its upper end with the main frame, serves to retract the key bar and hold the same normally in its retracted position. If desired, a full stroke device may be provided to make it necessary to complete the movement of the key bar in the direction in which it has been started before that movement may be reversed and, in the present construction I have shown a spring held pawl 48 arranged to engage ratchet teeth 49 on the lower edge of the key bar and lock the key bar against return movement until the rack has been moved past the pawl to permit the latter to reverse itself.

55 The actuating member 38 is supported normally in a position out of line with the contact portions of both ejector arms but the supporting means is of such a character that the actuating member may, under the control of the coin in the chute, be moved into line with the contact portion of either ejector arm. In that form of the mechanism here shown the support for the actuating member is in the form of a guide pin 50 carried by the downturned end of a substantially horizontal lever or rack arm 51 which is pivotally mounted at its opposite end on a stud 52 carried by the main frame. Rigidly connected with the arm 51 is a downwardly extending arm 53 having its lower portion arranged to be engaged by a coin in the coin chute. Preferably the arm 53 has its lower portion offset, as shown at 54, so that it may enter a slot 55 in the front wall of the coin chute. A spring 56 acts on the arm 53 to hold the offset portion or projection 55 normally in the slot where it may be engaged by the edge of a coin supported within the chute. Arranged on the opposite side of the coin chute is a coin actuating device here shown in the form of an arm 57 pivotally mounted on the main frame at 58 and extending upwardly and forwardly so that its upper portion may have approximately horizontal movement in a slot 59 in the rear wall of the coin chute, thus enabling the coin actuating arm to engage a coin in the chute and press the same against the arm 53 of the controlling device for the actuating member. The movement of the coin actuating arm 57 is the

same upon all operations of the mechanism and therefore the amount of movement imparted to the arm 53 will depend upon the diameter or value of the coin, it being obvious that a five cent coin or nickel will move the arm a greater distance than it will be moved by a ten cent coin or dime. Rigidly connected with the coin actuating arm 57 is a crank arm 60 having a stud 61 adapted to ride upon a cam surface 62 on the key bar 43. A spring 63 acts on the coin actuating arm 57 to hold the stud 61 in contact with the cam. The cam is so shaped that the initial movement of the key bar will cause the coin actuating arm to enter the chute and if there is a coin in the chute to press that coin against the arm 53 of the controlling device, thereby lowering the supporting guide 50 for the actuating member and permitting that member to move downwardly into line with one or the other of the ejector arms, as determined by the diameter of the coin. The actuating member is held in contact with and caused to follow the movement of the supporting guide 50 by a spring 64 which connects the same with the support 39. At the same time that the actuating member is being pivotally adjusted in the manner above described longitudinal or operative movement is being imparted thereto but the distance which the actuating member must travel before it engages either of the ejector arms is sufficient to permit the pivotal adjustment of the actuating member to be completed before it reaches the ejector arms.

It will be noted that the contact faces of the coin actuating arm 57 and of the controlling arm 53 are so arranged that when in contact with a coin they will diverge downwardly, thus facilitating the escape of the coin when the detent 33 is withdrawn. However, I prefer to positively release the coin and to this end I have provided the actuating member 38 on its lower edge with a cam surface 65 which is so arranged that it will engage the guide pin 50, after the actuating member has engaged the contact portion of one of the ejector arms, and will rock the controlling device 51-53 about its axis so as to move the part 54 of the arm 53 out of contact with the coin, thus releasing the same and preventing any possibility of its hanging in the chute after the detent has been withdrawn.

The checks vended by this machine are approximately the size of a dime and have formed therein a central opening to accommodate the same to the controlling mechanism for the telephone. To prevent one of these checks being deposited in the coin chute and used in place of a dime to cause the machine to discharge two other checks I have provided a mechanism which will prevent the operation of the ejecting mechanism when such a check, or other apertured device, is

deposited in the coin chute. For this purpose the supporting structure 34, which carries the detent 33 at the lower end of the chute, has mounted thereon a projection or pin 66 adapted to be projected through an opening 70 in the side wall of the chute by the inward movement of the structure 44. An arm 68 which extends upwardly from the structure 34 carries a pin or stud 69 which is so arranged that when the structure 34 is in its normal position the pin 69 will be in a position in which it will not interfere with the pivotal movement of the actuating member. The structure is retained in its normal position by a cam 70 projecting laterally from the key bar 43 and adapted to engage a projection or roller 71 carried by the structure 34. The lower end of this cam 70 is of such a width that it will support the structure 34 in its normal position, that is, with the detent or lip 33 in an operative position beneath the coin chute and with the projection 66 withdrawn from the chute. The intermediate portion of the cam, which is shown at 72 is of less width than the lower portion thereof and the lower portion is of such length that the initial movement of the key bar 43 will cause the intermediate portion to pass into engagement with the roller 71 of the structure 34, thus releasing that structure for inward movement. If there is a coin in the chute 32 the projection 66 will engage the face of that coin and will prevent the structure 34 from moving inwardly far enough to carry the pin 69 on the arm 68 into the path of the pivotal movement of the actuating member 38, thus leaving that member free to follow the movement of the guide pin 50. If there is a check within the coin slot, or a washer or other apertured device, the projection 66 will pass through the opening therein, thus permitting the structure 34 to move inwardly far enough to carry the pin 69 beneath the actuating member, thereby preventing its movement with the guide pin 50 when the latter is moved downwardly and consequently rendering the actuating member inoperative. The upper portion 73 of the cam is of a width greater than the width of the lower portion thereof and when this upper portion contacts with the roller 71 on the structure 34 that structure is moved downwardly far enough to withdraw the projection 66 from the coin chute and to withdraw the detent 33 from beneath the chute, thus opening the chute and permitting the coin therein to drop into the coin box 74. The projection 66 on the structure 34 is pivotally mounted, as shown at 75, to prevent interference with the movement of a coin with which it is in contact, and it is held normally in a central position by the spring 76 and a stop 77.

The delivery chute 17 extends from the discharge openings 16 for the magazines downwardly and forwardly and at its lower

end opens into a delivery receptacle 78. This delivery receptacle has in its front wall an opening 79, through which the check or other article may be removed, and its bottom wall 80 slopes downwardly and rearwardly from that opening. The lower wall of the chute 17 projects forwardly a slight distance beyond the rear wall of the delivery receptacle, as shown at 81, and the upper wall of the chute is curved downwardly and rearwardly, as shown at 82, and terminates at a point in line with but spaced from the front edge of the lower wall of the chute. As a result when a check slides down the chute 17 and off the lower end thereof it will engage the downwardly and rearwardly extending front end of the upper wall of the chute and will be deflected downwardly against the rear wall of the delivery receptacle, which in turn will deflect it against the inclined bottom wall 80, the angle of contact with the inclined bottom wall being such that it will bounce upwardly and rearwardly and then drop back into the delivery receptacle. In this way I prevent the checks from bouncing out of the delivery receptacle and overcome a very common source of annoyance in machines of this kind.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a coin controlled apparatus having a plurality of parts to be operated, an actuating member to actuate a selected one of said parts to be actuated, a coin controlled device to position said actuating member in operative relation to one of said parts to be operated, and means for imparting operative movement to said actuating member.

2. In a coin controlled apparatus having a plurality of parts to be operated, an actuating member to actuate a selected one of said parts to be actuated, an adjustable guide to control the position of said actuating member with relation to said parts to be operated, coin controlled means to adjust said guide, and means for imparting operative movement to said actuating member.

3. In a coin controlled apparatus comprising a plurality of parts to be operated, each having a contact portion, an actuating member mounted for transverse movement into line with the contact portion of a selected part to be operated and for longitudinal movement to actuate the selected part to be operated, a coin controlled device to control the transverse movement of said actuating member, and means for imparting longitudinal movement to said actuating member.

4. In a coin controlled apparatus having a plurality of parts to be operated, each having

a contact portion, an actuating member, a movable support on which said actuating member is pivotally mounted for movement into line with the contact portion of a selected part to be operated, coin controlled means to control the pivotal movement of said actuating member, and means for actuating said support to impart operative movement to said actuating member.

5. In a coin controlled apparatus having a plurality of parts to be operated, each having a contact portion, an actuating member, a movable support on which said actuating member is pivotally mounted for movement into line with the contact portion of a selected part to be operated, an adjustable guide to control the pivotal movement of said actuating member, coin controlled means to adjust said guide, and means for actuating said support to impart operative movement to said actuating member.

6. In a coin controlled apparatus comprising a coin chute and a plurality of parts to be operated, each having a contact portion, an actuating member mounted for transverse movement into operative relation to the contact portion of a selected part to be operated and for longitudinal movement to actuate said selected part, an adjustable device to control the transverse movement of said actuating member and having a part arranged to be engaged by a coin in said chute, a second device to cause said coin to impart movement to said controlling device proportionate to the diameter of said coin, and means to actuate the last mentioned device and to impart longitudinal movement to said actuating member.

7. In a coin controlled apparatus comprising a coin chute and a plurality of parts to be operated, each having a contact portion, an actuating member mounted for transverse movement into operative relation to the contact portion of a selected part to be operated and for longitudinal movement to actuate said selected part, an adjustable device to control the transverse movement to said actuating member and having a part arranged to be engaged by a coin in said chute, a second device to cause said coin to impart movement to said coin controlling device proportionate to the diameter of said coin, and a reciprocatory operating member having means to actuate the last mentioned device and to impart longitudinal movement to said actuating member.

8. In a coin controlled apparatus comprising a coin chute and a plurality of parts to be operated, each having a contact portion, an actuating member mounted for transverse movement into operative relation to the contact portion of a selected part to be operated and for longitudinal movement to actuate said selected part, an adjustable device to con-

- trol the transverse movement of said actuating member and having a part arranged to be engaged by a coin in said chute, a second device to cause said coin to impart movement to said coin controlling device proportionate to the diameter of said coin, means to actuate the last mentioned device and to impart longitudinal movement to said actuating member, and means to actuate said controlling device to release the coin after said actuating member has engaged the contact portion of the selected part to be operated.
9. In a coin controlled apparatus comprising a coin chute and a plurality of parts to be operated, an actuating member, a movable support on which said actuating member is pivotally mounted for movement into operative relation to a selected part to be operated, a pivoted arm having at its free end a part to control the pivotal movement of said actuating member, a second arm connected with said controlling arm and having a part positioned at one edge of said chute to be engaged by a coin in said chute, a movable device having a part to enter said chute and cause said coin to engage said second arm and move the first mentioned arm a distance proportionate to the diameter of said coin, and an operating device having means to actuate said movable device and to cause said movable support to impart operative movement to said actuating member.
10. In a coin controlled apparatus comprising a coin chute and a plurality of parts to be operated, an actuating member, a movable support on which said actuating member is pivotally mounted for movement into operative relation to a selected part to be operated, a pivoted arm having at its free end a part to control the pivotal movement of said actuating member, a second arm connected with said controlling arm and having a part positioned at one edge of said chute to be engaged by a coin in said chute a movable device having a part to enter said chute and cause said coin to engage said second arm and move the first mentioned arm a distance proportionate to the diameter of said coin, an operating device having means to actuate said movable device and to cause said movable support to impart operative movement to said actuating member, and means carried by said actuating member to impart outward movement to said second arm after said actuating member has engaged a selected part to be operated.
11. In a coin controlled apparatus comprising a coin chute and a plurality of parts to be operated, an actuating member to impart movement to a selected part to be operated, means controlled by a coin in said chute to control the position of said actuating member with relation to said parts to be operated, means to impart operative movement to said actuating member, an auxiliary device to retain said actuating member in an inoperative position with relation to said parts to be operated, and means controlled by a coin in said chute to hold said auxiliary device in an inoperative position with relation to said actuating device.
12. In a coin controlled apparatus comprising a coin chute and a plurality of parts to be operated, an actuating member to impart movement to a selected part to be operated, a guide to retain said actuating member normally in an inoperative position with relation to said parts to be operated, means controlled by a coin in said chute for adjusting said guide to position said actuating member in operative relation to a selected part to be operated, means to impart operative movement to said actuating member, an auxiliary device movable into a position to retain said actuating member in its inoperative position, and means controlled by a coin in said chute to prevent the movement of said auxiliary device to said position.
13. In a coin controlled apparatus comprising a coin chute and a plurality of parts to be operated, an actuating member to impart movement to a selected part to be operated, a guide to retain said actuating member normally in an inoperative position with relation to said parts to be operated, means controlled by a coin in said chute for adjusting said guide to position said actuating member in operative relation to a selected part to be operated, means to impart operative movement to said actuating member, an auxiliary device movable into a position to retain said actuating member in its inoperative position, means controlled by the operating means for said actuating member to normally hold said auxiliary device out of said retaining position and to release the same during the initial movement of said operating means, and means controlled by a coin in said chute to prevent the movement of said auxiliary means to said retaining position after it has been released.
14. In a coin controlled apparatus comprising a coin chute and a plurality of parts to be operated, an actuating member to impart movement to a selected part to be operated, a guide to retain said actuating member normally in an inoperative position with relation to said parts to be operated, means controlled by a coin in said chute for adjusting said guide to position said actuating member in operative relation to a selected part to be operated, means to impart operative movement to said actuating member, a structure mounted for movement toward and from said coin chute, yieldable means to move said structure toward said coin chute, projection carried by said structure and adapted to enter said coin chute when its movement is not obstructed by a coin, and a stud carried by said structure and so ar-

ranged that when said projection enters said coin chute said stud will be moved to a position to retain said actuating member in its inoperative position.

5 15. In a coin controlled apparatus comprising a coin chute and a plurality of parts to be operated, an actuating member to impart movement to a selected part to be operated, a guide to retain said actuating member normally in an inoperative position with relation to said parts to be operated, means controlled by a coin in said chute for adjusting said guide to position said actuating member in operative relation to a selected 10 part to be operated, means to impart operative movement to said actuating member, a structure mounted for movement toward and from said coin chute, yieldable means to move said structure toward said coin chute, a projection carried by said structure and adapted to enter said coin chute when its movement is not obstructed by a coin, a stud carried by said structure and so arranged that when said projection enters said coin chute said stud 15 will be moved to a position to retain said actuating member in its operative position, and means controlled by the operating means for said actuating member to move said structure from said coin chute.

20 16. In a coin controlled apparatus comprising a coin chute and a plurality of parts to be operated, an actuating member to impart movement to a selected part to be operated, a guide to retain said actuating member normally in an inoperative position with relation to said parts to be operated, means controlled by a coin in said chute for adjusting said guide to position said actuating member in operative relation to a selected part to 25 be operated, means to impart operative movement to said actuating member, a structure mounted for movement toward and from said coin chute, yieldable means to move said structure toward said coin chute, a projection carried by said structure and adapted to enter said coin chute when its movement is not obstructed by a coin, a stud carried by said structure and so arranged that when said projection enters said coin chute said stud 30 will be moved to a position to retain said actuating member in its operative position, said projection being pivotally mounted to permit movement of a coin with which it is in contact.

35 17. In a coin controlled apparatus comprising a coin chute and a plurality of parts to be operated, an actuating member, a movable support on which said actuating member is pivotally mounted for movement into operative relation to a selected part to be operated, a pivoted arm having at its free end a part to control the pivotal movement of said actuating member, a second arm connected with said controlling arm and having a part positioned at one edge of said chute to be en-

gaged by a coin in said chute, a movable device having a part to enter said chute and cause said coin to engage said second arm and move the first mentioned arm a distance proportionate to the diameter of said coin, a structure mounted for movement toward and from said coin chute, yieldable means to move said structure toward said coin chute, a projection carried by said structure and adapted to enter said coin chute when its movement is not obstructed by a coin, a stud carried by said structure and so arranged that when said projection enters said coin chute said stud will be moved to a position to retain said actuating member in its inoperative position, an operating device to actuate said support and impart operative movement to said actuating member, cam means connected with said operating device and arranged to hold said structure normally in its retracted position, to release said structure for movement toward said coin chute during the initial movement of said operating device, and to retract said structure during the latter part of the movement of said operating device.

40 In testimony whereof, I affix my signature hereto.
